PULL

John R. Morgan, Chicago, Ill., assignor to Amerock Corporation, Rockford, Ill., a corporation of Illinois

Filed Nov. 2, 1961, Ser. No. 67,364

Term of patent 14 years

(Cl. D10—8)

FIGURE 1 is a perspective view of a pull embodying my new design.

FIG. 2 is a top plan view thereof.

FIG. 3 is a front elevational view of the pull.

FIG. 4 is a side elevational view taken from the left side of FIG. 1.

FIG. 5 is an enlarged sectional view taken along the line 5—5 in FIG. 3.

The characteristic feature of my design resides in the specific configuration of the trapezoidal shaped handle member in association with the mounting flanges, as best shown in FIGS. 1, 2 and 3.

I claim:

The ornamental design for a pull, substantially as shown and described.
